UNITED STATES PATENT OFFICE.

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA.

CONDENSER.

Application filed August 3, 1926. Serial No. 126,772.

This invention relates to steam condensers of the surface type, and the primary object of the invention is to provide a condenser in which leakage of cooling water, circulated through the tubes of the condenser, into the steam chamber and its mixing with the condensate will be prevented.

In steam condensers the temperature of the tubes is constantly fluctuating and the difference between the temperature of the tubes adjacent to the steam inlet and those remote therefrom, of a condenser operating with the varying load is constantly fluctuating through a wide range. Because of this it has heretofore been the practice to provide stuffing box connections for one or both ends of the tubes with the tube heads in order to accommodate the expansion and contraction of the tubes. Such stuffing box connections are objectionable for various reasons, one of which is the difficulty in avoiding leakage, especially as the temperatures to which they are sometimes subjected are so high as to injuriously affect the packing in the stuffing boxes so that leakage results. In the present pure water power plant systems, where boiler feed water is purified by degasification, etc., to eliminate to the greatest possible extent corrosion and other detrimental actions on the boiler tubes, pumps, etc., employed in the power plant, it is highly desirable to prevent the circulating cooling water, which is not treated for purification, from leaking from the tubes and mixing with the condensate or boiler feed water as such mixing counteracts to a certain extent the action of the purifying mechanism of the system.

To overcome such leakage it is necessary to provide fluid tight connections between the tubes and tube heads of the condenser, and in so doing cognizance must be taken of and compensation made for variances in the temperatures in the condenser, variances in the expansion and contraction relation of the tubes with the shell or casing of the condenser and also difference in temperatures locally within the condenser, whereby the tubes in one set or bank or in one location of the interior of the condenser will be subjected to greater or less temperatures and temperature variances than tubes in another part of the condenser.

It is an object of the present invention

to provide a condenser construction which will permit a fluid tight connection between the tubes and tube heads and will compensate for variances in temperatures and conditions as outlined above.

The present invention embodies a condenser having a floating water box to which one of the tube heads is attached and an expansion joint between the tube head and condenser shell to permit movement of the tube head and water box relative to the condenser shell to compensate for expansion and contraction of the condenser tubes under heat variances, and it also embodies adjustable pivotal supporting connection between the condenser shell and the water box to permit movement of the water box to compensate for localized variances of temperatures within the condenser.

With these objects in view, the invention consists in various features of construction and combination of parts, which will be first described in connection with the accompanying drawings, showing a condenser of the preferred form embodying the invention, and the features forming the invention will be specifically pointed out in the claims.

In the drawings—

Figure 1 is a side elevation of a condenser constructed in accordance with this invention.

Figure 2 is a slightly enlarged elevation of one end of the condenser having parts broken away.

Figure 3 is an end view of the condenser having parts broken away and

Figure 4 is a slightly enlarged detail section illustrating the expansion joint connection between the condenser shell and tube head and water box.

Referring more particularly to the drawings, the surface condenser comprises the shell 1 having an exhaust steam inlet 2 through which the exhaust steam to be condensed enters the condenser and passes therethrough transversally to the tubes 3 which extend longitudinally through the shell 1 of the condenser. Cooling water for condensing the steam is circulated through the tubes 3 and water boxes 4 and 5, while the condensate passes to the hotwell 6 from which it is drawn in any suitable manner. To prevent leakage of the circulated cooling water

into the condensate chamber and its resulting mixing with the condensate, the tubes 3 are expanded into the tube heads, one of which is shown at 6 in Figures 2 and 4 of the drawings. While the tubes 3 are shown expanded into the tube heads, it is to be understood that they may be connected to the tube heads in any suitable manner so as to provide a fluid tight joint.

Owing to the fluctuation of temperatures within a condenser operating upon varying loads, it is necessary to provide compensation for the expansion and contraction of the tubes 3 under the heat variances so as to prevent rupturing of the connections between the tubes and tube heads. In the present embodiment of the invention as shown in the drawings, the tube head 6 is attached to the water box 5 and is free from connection with the shell 1 of the condenser except through the expansion joint 7 which is a gasket of flexible material, preferably rubber or a composition of rubber and cloth, or any suitable material found adaptable for the purpose, which will not corrode or deteriorate upon contact with the water and steam in the condenser shell. The gasket 7, which forms the expansion joint is clamped against and attached to the flange 8 on the shell 1 by a clamping ring 9, as clearly shown in Figure 4 of the drawings.

Owing to the fact that the temperature of the tubes 3 in certain localities within the shell 1 is greater and fluctuates more than the temperatures of tubes in other portions of the shell 1, provision is made to permit of a pivotal or rocking movement of the water box 5 and the tube head 6, relative to the shell 1; and this provision is made through the adjustable pivotal joint structure 10.

The adjustable pivotal joint structure 10 comprises bracket plates 11 which are attached to brackets 12 formed on the shell 1. Arms 13 are pivotally connected, as shown at 14, to the bracket plates 11 and are adjustably connected through the medium of turnbuckles 15 with corresponding arms 16 which are pivotally mounted upon studs 18 threaded into suitable bosses 19. The bosses 19 are formed on the water box 5 in alignment with the horizontal axis of the water box. The pivotal connection of the arms 13 and 16 to the shell 1 and the water box 5 respectively, will permit a pivotal movement of the water box on its horizontal axis and a corresponding movement of the tube head 6 to compensate for variances in the expansion and contraction of the tubes above and below the point of pivotal connection with the water box.

It will be understood that the invention is not to be limited to the specific construction or arrangement of parts shown but that these may be modified widely within the invention defined by the claims.

What is claimed is:

1. In a surface condenser, a shell, a water box, a tube head carried thereby, a flexible connection between the water box and shell, and means connecting said water box and shell to permit pivotal movement of the water box relative to the shell.
2. In a surface condenser, a shell, a water box, and a rockable supporting connection between said shell and water box to permit pivotal movement of the water box relative to the shell.
3. In a surface condenser, a shell, a water box, and adjustable rockable supporting connection between said shell and water box to permit pivotal movements of the water box relative to the shell.
4. In a surface condenser, a shell, a water box, supporting rods pivotally connected to said water box and said shell to permit pivotal movement of the water box relative to the shell.
5. In a surface condenser, a shell, a water box, an expansion joint between the water box and shell, and supporting rods pivotally connected to said water box and said shell to permit pivotal movement of the water box relative to the shell.
6. In a surface condenser, a shell, a water box, adjustably connected supporting rods pivotally connected to said water box and to said shell to permit pivotal movement of the water box relative to the shell.
7. In a surface condenser, a shell, a water box, and adjustable means pivotally connecting said water box and shell.
8. In a surface condenser, a shell, a water box, an expansion joint between said water box and shell, and adjustable means pivotally connecting said water box and shell.
9. In a surface condenser, a shell, a water box, a tube head, a flexible gasket engaged between said tube head and water box and attached to said shell for forming an expansion joint between the shell and water box and tube head, and supporting connections between the water box and shell to permit movement of the water box and tube head relative to the shell.
10. In a surface condenser, a shell, a water box, a tube head carried thereby, tubes having fluid tight connection with said tube head, a fluid tight expansion joint between said water box and shell, and adjustable means pivotally connecting said water box and shell.
11. In a surface condenser, a shell, a water box, a tube head carried thereby, tubes having fluid tight connection with said tube head, a fluid tight expansion joint between said water box and shell, supporting rods pivotally connected to said water box in the horizontal plane passing through its axis and pivotally connected to said shell adjacent to its top.

12. In a surface condenser, a shell, a water box, adjustably connected supporting rods pivotally connected to said water box in the horizontal plane passing through its axis and pivotally connected to said shell adjacent to its top to permit swinging pivoted movement of the water box relative to the shell.
13. In a condenser, a shell, a water box, brackets on said shell adjacent to its top, rods pivotally connected to said brackets, rods pivotally connected to said water box in the horizontal plane passing through its axis, and adjustable means connecting the water box carried rods to the corresponding bracket carried rods.
14. In a condenser, a shell, a water box, brackets on said shell adjacent to its top, rods pivotally connected to said brackets, rods pivotally connected to said water box in the horizontal plane passing through its axis, adjustable means connecting the water box carried rods to the corresponding bracket carried rods, and a fluid tight expansion joint between said water box and shell.

In testimony whereof I affix my signature.

JOHN F. GRACE.
